WALTER BOX, OF GEORGETOWN, TEXAS.

INTERNAL-COMBUSTION ENGINE.

1,213,068.

Specification of Letters Patent. Patented Jan. 16, 1917.

Application filed February 11, 1916. Serial No. 77,735.

To all whom it may concern:

Be it known that I, WALTER BOX, a citizen of the United States, and a resident of Georgetown, in the county of Williamson and State of Texas, have invented a certain new and useful Improvement in Internal-Combustion Engines, of which the following is a specification.

My invention relates to internal combustion engines, and it consists in the combinations, constructions, and arrangements herein described and claimed.

An object of my invention is to provide an engine having a rotary valve adapted to be continuously driven in one direction and so arranged that a charge will be drawn in, ignited, and exhausted in regular sequence, thereby driving the engine continuously.

In the drawings: Figure 1 is a vertical section through the cylinder of an engine provided with the improved valve. Fig. 2 is a top plan view of the valve with parts in section. Fig. 3 is a view at right angles to Fig. 2. Figs. 4 and 5 are sections on the lines 4-4 and 5-5 respectively, of Fig. 2. Fig. 6 is a diagrammatic view showing the valve in exhaust position. Fig. 7 is a similar view showing the valve in inlet position. Fig. 8 is a central longitudinal sectional view through the device. Fig. 9 is a bottom view of the cylinder head. Fig. 10 is a view of a portion of a modified form of the device.

In carrying out my invention, I provide a cylinder 1 having a piston 2, which is connected with the crank 3 of the crank-shaft 4, by means of the piston rod 5, and the cylinder is jacketed at the outer end as indicated at 6. The intake port 7 of the cylinder and the exhaust 8 open from opposite sides of the cylinder into a common cylindrical valve chamber 9 formed in the cylinder head and from which leads a port or passage 10 into the cylinder. The valve is a cylindrical body 11 having solid ends and chambered intermediate its ends. At one end the valve is provided with an external gear ring 12 for engagement by suitable operating mechanism to rotate the valve and at the inner end of each of the solid portions the valve has external annular grooves 13 for receiving packing rings 14. Between the packing rings the valve is chambered. At the end of the chambered portion remote from the ring 12, the valve

is cut away at opposite sides to form ports or passages 15 communicating with the chambered interior of the valve. At the opposite end of the chambered portion the 60 valve has a port or passage 16, and the said port or passage is of much less width than the passages 15 and communicates with the chamber of the valve and has its long axis in alinement with the long axis of the adjacent passage 15. From each side of the port or passage 16 the valve is recessed on its outer face as indicated at 17 over a depth sufficient to receive a packing ring 18, the 65 said ring being a split ring and extending 70 from near one side edge of the port or passage 16 to near the other, as shown. The port or passage 10 is designed to communicate by means of the cylindrical chambered portion 9 of the valve with the intake 7 75 and the exhaust 8 through the ports 15. The latter are designed to register with the combustion chamber of the engine and with the spark plug 19 whereby the interior of the valve constitutes in fact a part of the 80 combustion chamber.

It will be understood that the intake and the exhaust are offset with respect to the combustion chamber and that the entering charge passes by way of the port 7 85 through the port 16 to the interior of the valve and the ports 15 permit the spark plug to ignite the charge within the valve and cylinder.

The valve is of a length to extend entirely 90 through the cylinder head, and the end carrying the gear 12 may be provided with a fan to cool the motor.

In use, when the valve is in the position of Fig. 7, the charge may enter by way of the port 7, the port 16, and by way of the chambered interior of the valve, and the ports 15 by way of the port 10 to the cylinder. At the proper time the charge will be ignited by the spark plug 19 at the time 95 100 the ports 15 register with the spark plug and with the port 10. A further movement of the valve will bring the port 16 in register with the exhaust 8 as indicated in Fig. 6, and the products of combustion may pass 105 out by way of the ports 15 and 16. The ports 15 are of such size that the said ports will lap or register with the port 10, while the port 16 is in register with the port 7 or 8. The port 16 is of the same width as the ports 110 7 and 8 and during the explosion of the charge, the said port is out of register with

both ports 7 and 8. Whenever the port 16 is in register with the intake, packing ring 18 will be over the exhaust port and whenever the port 16 registers with the exhaust, the said packing ring will be over the intake; at the time of explosion said ring will cover both the intake and the exhaust. In a multicylinder engine, it will be understood that there will be a section of the valve for each cylinder, but will all be made in one piece.

It will be understood that the valve through the gear ring 12 is connected to a moving part of the engine, to cause the valve 15 to rotate one half the crank shaft speed, and both crankshaft and valve rotate in the direction of the arrows shown adjacent to the same, that is, clockwise. When the spark plug is removed, one may look directly into 20 the combustion chamber.

At each side of the ring 18 there is a small pin, these pins being used for pulling the ring. They may be placed anywhere on the ring. The clutches must be placed on 25 the edge as shown.

In Fig. 8 I have shown a modified form 30 of the device, in which a sleeve 20 may be inserted in the cylinder head to form a bushing or bearing for the rotatable valve. It may be that the builder of the engine 35 wants to use a metal that is not suitable for a bearing, and in such case he may insert the sleeve and finish it off on the inside so that the valve will rotate within the sleeve. This sleeve is provided with ports 21 and 22 arranged to register with the intake and 40 exhaust ports respectively, while the opening 23 registers with the passage 15 in the valve. It will be seen that in this form of the device a sleeve merely forms a suitable bearing for the valve, where the body portion of the engine itself can not so be used.

I claim:—

1. In combination with the cylinder of an internal combustion engine having a substantially cylindrical valve chamber at the outer end thereof and extending transversely thereof, said cylinder having a port opening into the combustion chamber and a cylinder having aligned oppositely extending intake and exhaust ports at the valve chamber and at right angles to the port leading to the cylinder and offset longitudinally with respect to the first named port and having igniting mechanism at the opposite side of the chamber from the first named port, of a rotary valve in the chamber and extending at its ends beyond the said chamber and having at one end a gear ring for connecting with means for rotating the valve continuously in one direction, the ends of the valve being solid and the intermediate portion being chambered, said valve having annular packing grooves at the inner ends of the solid 60 portions, and packing rings in the grooves,

said valve having a radial longitudinally extending slot forming a port at the end of the chambered portion adjacent to the gear ring, and having a depression extending longitudinally of the valve at said port and from one side thereof around the valve to near the other side thereof, a packing ring in the depression, said port registering with the inlet and the exhaust, and the valve having oppositely arranged ports at the other end of the chambered portion registering with the spark plug and the first named port of the cylinder.

2. In combination with the cylinder of an internal combustion engine having a substantially cylindrical valve chamber at the outer end thereof, and having a port leading from the chamber into the cylinder, said chamber having oppositely extending inlet and exhaust ports, and having igniting mechanism opposite the first-named port, a valve mounted to rotate in the chamber and of substantially cylindrical form, said valve being chambered intermediate its ends and having a port adapted to register in alternation with the inlet and the exhaust and having oppositely arranged ports for registering with the first named port and the igniting mechanism, the valve having means for sealing the port with which the first named port is out of register.

3. In an internal combustion engine, a cylinder, a head therefor, a spark plug disposed in said head, said head being provided with a bore and having intake and exhaust passages communicating with the bore, and a port extending from the bore to the interior of the cylinder, a cylindrical valve closed at its ends and having a hollow portion intermediate its ends, said valve being arranged to enter the bore and being provided with a port arranged to register with the intake and exhaust passages, a second port arranged to register with the port leading into the cylinder, and a third port arranged to register with the spark plug.

4. In an internal combustion engine, a cylinder, a head therefor, a spark plug disposed in the head, said head being provided with a bore and having intake and exhaust passages communicating with the bore, and a port extending from the bore to the interior of the cylinder, a hollow portion intermediate its ends, said valve being arranged to enter the bore and being provided with a port arranged to register with the intake and exhaust passages, a second port arranged to register with the port leading into the cylinder, and a third port arranged to register with the spark plug, said second named and said third named ports being disposed on opposite sides of the valve.

5. In an internal combustion engine, a cylinder, a head therefor, a spark plug disposed in the head, said head being provided

with a bore and having intake and exhaust passages communicating with the bore, a port extending from the bore to the interior of the cylinder, a hollow portion intermediate its ends, said valve being arranged to enter the bore and being provided with a port arranged to register with the intake and exhaust passages, a second port ar-

ranged to register with the port leading into the cylinder, and a third port arranged to register with the spark plug, said second named and said third named ports being disposed on opposite sides of the valve and being in alinement.
